[57] CLAIM

The ornamental design for a spray dispenser or similar article, as shown and described.

DESCRIPTION

FIG. 1 is a top perspective view of a spray dispenser or similar article showing my new design;

FIG. 2 is a top plan view thereof;

FIG. 3 is a front elevational view thereof, the side opposite being a mirror image of the side shown;

FIG. 4 is a left side elevational view thereof; the side opposite being a mirror image of the side shown;

FIG. 5 is a front elevational view shown with the cap removed for clarity of illustration;

FIG. 6 is a left side elevational view thereof;

FIG. 7 is a top plan view thereof; and

FIG. 8 is a bottom plan view thereof.

FIG. 1

FIG. 2
